JET-OPERATED ROTARY LIFTING DEVICE

Byron J. Kerry, Dearborn, Mich.

Application August 17, 1950, Serial No. 180,013

11 Claims. (Cl. 170—135.4)

1

This invention relates to aircraft and in particular to aircraft operated by jet-propulsion.

One object of this invention is to provide a jet-operated rotary lifting device for aerial navigation wherein the lifting power is provided by the products of combustion of hydrocarbon fuel ejected from the device in a rotary path with an upward component from each jet.

Another object is to provide a jet-operated rotary lifting device as set forth in the preceding object wherein the device is provided with hollow radial blades through which the fuel conduits pass and which also provide an additional lifting effect by the tangentially acting jets at the outer ends of the blades.

Another object is to provide a jet-operated rotary lifting device as set forth in the preceding objects wherein the fuel is ignited in a chamber within a central casing and passes through the hollow blades to the exhaust ports where the jet reaction occurs, the latter being supplemented by the reaction effect obtained from additional fuel piped to the discharge ports of the rotor at the tips of the blades.

Another object is to provide a jet-operated rotary lifting device, as set forth in the preceding objects wherein the fuel is forced outward to the ends of the blades by scoop tubes operating in a central fuel chamber and acting under the influence of the centrifugal force generated by the rotation of the device.

Another object is to provide a jet-operated rotary lifting device, as set forth in the preceding objects, wherein air is supplied to a combustion chamber by means of spiral vanes terminating in external scoops.

Another object is to provide a jet-operated rotary lifting device, as set forth in the preceding objects, wherein the combustible mixture of hydrocarbon fuel and air is brought together and ignited by a wick located in a flue passing through the center of a fuel tank, thereby also heating the fuel tank and generating pressure therein which enhances the action of the fuel scoop tubes operating in the fuel tank.

Another object is to provide a jet-operated rotary lifting device, as set forth in the preceding objects, wherein the flue containing the wick opens into a pressure dome into which a portion of the fuel is sprayed across the top of the flue and ignited by the flame rising from the wick.

Another object is to provide a jet-operated rotary lifting device, as set forth in the preceding objects, wherein the rotor assembly including the central casing is provided with means for tilting the assembly relatively to the support on which

2

it is mounted, in directions at right angles to one another.

In the drawings:

Figure 1 is a top plan view of a jet-operated rotary lifting device, according to a preferred form of the invention;

Figure 2 is a side elevation of the lifting device shown in Figure 1;

Figure 3 is an enlarged central vertical section through the central casing of the device, taken along the line 3—3 in Figure 1;

Figure 4 is a horizontal section through the rotor assembly tilting mechanism taken along the line 4—4 in Figure 1;

Figure 5 is an enlarged partially horizontal and partially inclined section through a portion of the periphery of the rotor taken along the line 5—5 in Figure 2;

Figure 6 is a horizontal section through the central casing showing the upper fuel tank and flue taken along the line 6—6 in Figure 3;

Figure 7 is a horizontal section through the central casing showing the air chamber, air scoops and vanes and the wick tube, taken along the line 7—7 in Figure 3;

Figure 8 is a vertical section through one of the hollow rotor blades, taken along the line 8—8 in Figure 1;

Figure 9 is a vertical section through the outlet in the end of one of the jet discharge tubes taken along the line 9—9 in Figure 2;

Figure 10 is a vertical section similar to Figure 8 but taken along the line 10—10 in Figure 1 nearer the central casing;

Figure 11 is a fragmentary horizontal section taken along the line 11—11 in Figure 3 immediately above the outlet of the central flue;

Figure 12 is an enlarged fragmentary vertical section through a modified jet-operated rotary lifting device, corresponding to the central portion of Figure 3;

Figure 13 is an enlarged partially horizontal and partially inclined section through a portion of the periphery of a modified rotor, corresponding in position to Figure 5;

Figure 14 is a vertical section through the outlet in the end of one of the jet discharge tubes of a modification of the invention, corresponding in position to Figure 9;

Figure 15 is a top plan view partly in horizontal section through the structure shown in Figure 14; and

Figure 16 is a diagrammatic view partly in vertical section of the fuel supply system used in the jet-operated rotary lifting device of the present invention.

General arrangement

Referring to the drawings in detail, Figures 1 and 3 inclusive show a jet-operated rotary lifting device according to a preferred form of the invention as consisting generally of a support 10, a central casing or power generating unit 11 rotatably mounted thereon, and a rotor assembly 12 mounted on the power generating unit 11. The rotor assembly 12 in turn consists of a plurality of impellers, generally designated 13. Four such impellers 13 are shown, but a greater or lesser number may obviously be employed instead of the four shown. Each impeller 13 consists of a hollow radial blade portion 14 of air foil cross section and screw arrangement having an arcuate circumferential jet discharge portion or tube 15 extending rearwardly from the tip thereof.

Power generating unit and support

The support 10 (Figure 3) is shown only in its upper portion and consists of a tubular member 16 rotatably mounted in a member 17 forming part of the fuselage of an aircraft or of a frame for carrying an operator, free rotation being accomplished by means of an anti-friction ball bearing unit 18 mounted in a recess 19 formed by a flange 20 on the member 17, the tubular member 16 having a flange 21 engaging the anti-friction bearing 18 after passing through a bore 22 in the member 17. The tubular member 16 terminates at its upper end in a hollow spherical portion 23 seated in a correspondingly spherical socket 24 in a portion 25 extending downwardly from the bottom of an egg-shaped central casing 26 which houses the power generating unit 11. The lower end of the portion 25 is internally threaded and stepped as at 27 to receive the correspondingly threaded and stepped upper edge 28 of a spherically curved retaining ring 29 screwed therein.

Mounted on the member 17 in locations spaced 90° circumferentially from one another are two angle brackets 30 (one only being shown in Figure 3) carrying pivot pins 31 on which the lower ends of two fluid pressure cylinders 32 are pivotally mounted. The cylinders 32 contain pistons 33, the upper ends of which carry clevises 34 connected by the pivot bolt 35 (Figure 4) to the brackets 36. The brackets 36 are mounted on and extend outward from the outer race 37 of an anti-friction bearing 38, the inner race of which is formed by the retaining ring 29. Connected to the outer ends of the cylinders 32 are pressure fluid supply conduits 39 and 40, preferably flexible, which lead to conventional control valves and a source of pressure fluid (Figure 16) such as a pump and a tank of fluid 43.

Leading upward from a hydrocarbon fuel tank (described below in connection with Figure 16) through the tubular portion 16 is a fuel supply conduit 44 which is connected through a ball connection 42 near its upper end to a conduit 43. The conduit 43 in turn is connected to a lower tank 45 in the lower end of the central casing 26. Above the tank 45 is a flanged partition 46 welded or otherwise firmly and tightly secured to the inner wall of the casing 26. The partition 46 (Figure 3) is provided with a port 47 from which a pipe 48 containing a check valve 49 leads upward to a port 50 in an approximately bell or trumpet-shaped flue 51 having an annular integral side wall 52 closed at the top by a flanged partition 53 welded or otherwise secured thereto and containing a central flanged opening 54

through which passes the top of the flue 51 and is tightly secured thereto. The flue 51, its side wall 52 and the partition 53 together form an upper fuel tank 55 to which liquid hydrocarbon fuel is supplied from the lower tank 45 by way of the pipe 48 and check valve 49, the latter preventing return flow of fluid. The side walls 52 of the tank 55 are pierced by annular internally threaded collars or bosses 56 in which are threaded closure plugs 57, thereby giving access to the interior of the tank 55.

The partition 46 and flue 51 define an air chamber 58 (Figure 3) having ports 59 through the side walls thereof (Figures 3 and 7) and air scoops 60 communicating therewith and extending partially around the lower portion of the central casing 26, these terminating at their outer ends in outer ports 61. Extending upward in a spiral path toward the flue 51 are spiral vanes 62, the inner edges of which are joined to a vertical air tube 63 having air ports 64 disposed vertically therein. The lower end of the air tube 63 is flanged as at 65 and is superimposed upon the flanged portion 66 of a wick tube 67, having spaced vertical ports 68 therein (Figures 3 and 7). The flanged portions 65 and 66 are supported by the partition 46 and the latter has a central hole 69 through which passes a wick 70 extending from the lower portion of the lower tank 45 up through the wick tube 67. Its upper end terminates within the flue 51 adjacent an igniter 71, such as a spark plug, mounted on and grounded to an upward extension 72 of the air tube 63. From the central terminal of the igniter 71 an electrical conductor 73 extends downward through a tube 74 into the support 10 and thence to a conventional source of high tension electricity such as a spark coil (not shown). The tubes 48 and 74 pass downward through holes in the spiral vanes 62 and the tube 74 likewise passes through holes 75 and 76 in the partition 46 and central casing 26 respectively. The flue 51 and air tube 63 are interconnected by radial members 77 (Figure 6).

Mounted spirally within the upper fuel tank 55 with their lower ends arranged circumferentially as scoop tubes in the lowermost part thereof (Figures 3 and 6) are main and secondary fuel pipes 78 and 79 respectively. The upper portions of the tubes 78 and 79 pass upward through ports 80 and 81 respectively in the partition 53 (Figure 3) into the pressure dome 82 forming the upper portion of the egg-shaped central casing 26. The secondary fuel pipes 79 immediately above the upper end of the flue 51 are provided with inwardly facing fuel outlet holes 83 (Figures 3 and 11) from which small jets of fuel spurt across the upper end of the flue 51 in the direction of the arrows, these being ignited by the flames coming up through the flue 51 from the upper end of the lighted wick 70.

Rotor assembly

The fuel pipes 78 and 79 continue through the interior of the pressure dome 82 and through converging inner ducts 84 (Figures 5, 8 and 10) located within the hollow blade portions 14 of the impellers 13. The blade portions 14 along their leading edges are provided with multiple air ports 85 (Figures 1 and 5).

The outer end of each inner duct 84 is of reduced diameter and is bent tangentially as at 86 where it opens into the jet discharge tube 15 (Figure 5). The secondary fuel tube 79 prior to its arrival at the curved end portion 86 of the

inner duct 84 is provided with a short branch tube 87 having orifices 88. The bent end portion 86 of the inner duct 84 is provided with a hole 89 (Figure 5) through which the main fuel pipe 78 passes and discharges into a nozzle ring 90 having jet spray orifices 91 arranged around the annular intake port 92 of the jet discharge tube 15 of the impeller 13.

The secondary fuel pipe 79 after passing through the bent end portion 86 of the inner duct 84 (Figure 5) passes through a hole 93 in the wall of the jet discharge portion 15 and emerges into the atmosphere for a short distance (Figure 8) thereafter passing through a hole 94 (Figure 9) adjacent the outlet end 95 of the jet discharge tube 15 of the impeller 13 immediately ahead of the impeller 13 from which it emerged. Beyond the hole 94, the tube 79 ends within one of the supporting arms 96 (Figure 9) of a dynamic pressure head 97 of hollow teardrop shape. The arm 96 in which the end of the secondary fuel tube 79 is seated has a transverse bore 98 leading into the interior of the dynamic pressure-head 97, and also a longitudinal or axial bore 99 leading therefrom toward the outlet end 95 of the jet discharge portion 15 of the impeller 13. The remaining arms 96 are also provided with transverse bores 98 leading from the interior of the dynamic pressure head 97 to a similar longitudinal bore 99 directed toward the outlet end 95 (Figure 9).

The jet discharge tubes 15 at their outlets 95 are inclined downward at an angle of approximately 9° (Figure 9) so as to give a lifting thrust as they rotate. The blade portions 14 are also inclined (Figures 3 and 8) so that their rotation as driven by the jet discharge tubes 15 generates a lifting thrust. The blade portions 14 also have ports 100 at their inner ends opening into the pressure dome 82.

Operation

Prior to operation, the various tanks 45 and 55 are filled with any volatile, combustible and rapidly expanding fuel, such as a hydrocarbon fuel. The fuel reaches the tank 55 from the tank 45 by way of the pipe 48 and check valve 49 (Figure 3). The wick 70 becomes saturated with the fuel and draws it upward by capillary attraction. When the fuel reaches the top of the wick 70, it vaporizes and fills the adjacent space in the flue 51 and rises into the pressure dome 82. The igniter 71 is then energized by energizing the conductor 73 with high tension electricity, causing a spark to jump across the electrodes thereof. This results in an explosion of the vapors within the flue 51, the exploding gases passing upward through the flue 51 and dome 82 into the inner ducts 84 within the blade portions 14, the gases passing outward through the jet discharge tube 15 and out the outlets 95 thereof, causing the rotor assembly 12 (Figure 1) to rotate in a clockwise direction by the reaction forces thus generated. As the central casing or power generating unit 11 rotates, the air scoop 61 and spiral vanes 62 force air upward into the flue 51 adjacent the wick 70, replacing the oxygen which has been burned during the initial explosion. Meanwhile, the heat generated within the flue 51 heats the fuel in the upper tank 55, vaporizing it partially and raising the pressure in the tank 55. The wick 70 continues to burn the fuel coming up through it by capillary attraction and the rotation of the power generating unit 11 causes the fuel tubes 78 and 79 to scoop up fuel and force it upward and out through the blade

portions 14 into the jet discharge tubes 15. Meanwhile, a portion of the air scooped up by the air scoop 61 and forced upward by the vanes 62 passes through the holes 64 in the air tube 63 surrounding the wick tube 67, mixing with a portion of the fuel escaping through the wick tube holes 68. Additional air for combustion is forced into the hollow blade portions 14 through the ports 85 (Figures 1 and 5) in the leading edges thereof.

The flue 51 because of its bell shape, acts as a venturi tube and the flame from the wick 70 ignites a portion of the fuel forced out through the holes 83 in the secondary fuel pipe 79 in the direction of the arrows (Figure 11) across the mouth of the flue 51. The gas thus ignited burns with a violent force and adds to the burning and exploding gases being ejected through the inner ducts 84 and out through the curved ends 86 thereof. A portion of the fuel is also sprayed out through the openings 88 in the branch tubes 87 (Figure 5) further boosting the impetus given by the reactive force already generated.

The reactive force is still further amplified by the burning of the spray of fuel from the jet openings 91 in the nozzle ring 90 mixing with air entering through the intake opening 92 of the jet discharge tubes 15 (Figure 5). These are of course ignited by the burning gases previously ignited. The burning gases continue to expand as they pass through the arcuate jet discharge tubes 15 and are given a final boost by the spray jet of fuel discharged from the jet openings 99 (Figure 9) in the dynamic pressure-heads 97, as supplied thereto by the secondary fuel pipes 79. The vaporization of the fuel in the pipes 78 and 79 is further enhanced by the heating of these pipes by the burning gases passing outward through the inner ducts 84 within the blade portions 14.

Meanwhile, in order to control the direction of flight, the operator supplies pressure fluid either to the cylinder 32 or 33 and pistons 35 thereof, rocking the rotating assembly upon the support 10 by means of the ball and socket joint therebetween. This action tilts the plane of the rotor assembly 12 in any desired direction, employing either of the cylinders 32 or 33 singly or with joint action thereof.

The machine is controlled by controlling the supply of fuel fed to the lower chamber or tank 45 through the pipe 44, by any suitable conventional valve (not shown). The foregoing action as described above causes the device to rotate with increased velocity according to the amount of fuel supplied to it.

Modified rotary lifting device

The modified jet-operated rotary lifting device, generally designated 110, shown in Figures 12 to 16 inclusive, closely resembles the device shown in Figures 1 to 11 inclusive and in many respects the construction is identical. Elements or portions of the rotary lifting device 110 which are identical or substantially identical with elements or portions of the rotary lifting device 10 are designated with the same reference numerals.

The central casing or power-generating unit 111 (Figure 12) is very similar to the central casing or power-generating unit 11 and differs only in the following respects. The central casing 26 which houses the power-generating unit 111 has an extension 112 of roughly bowl-shaped form into which the lower end of the fuel pipe 43 is threaded. A ball check valve 113 containing a

ball 114 in a cage 115 prevents backward flow of the fuel from the chamber 45 within the extension 112.

In place of the fuel feeding wick 70, the power generating unit 111 employs a primary jet or nozzle 116 which is threaded into a threaded bore 117 in a flanged tubular valve casing 118 which is secured to the underside of the partition 46 immediately below the hole 69 through which the wick formerly passed. A cup-shaped screen 119 protects the orifice 120 of the primary jet or nozzle 116 from being closed by foreign matter in the fuel, and extends downwardly into a chamber formed by a bore 121 from which a smaller bore 122 extends downwardly to a valve bore 123. The casing 118 is provided with vertically-spaced side wall ports 124 and 125 respectively opening into the upper and lower ends of the valve bore 123. Passageways 126 extend obliquely upward from the valve bore 123 from the level of the port 125 and open into elbows 127 connected to the bosses 128 in which the passageways 126 are located. Each elbow 127 contains a passageway 129 forming a continuation of the passageway 126 and closed by a ball check valve 130 pressed downwardly against the valve seat 131 by a compression spring 132 located in a counterbore 133. From the counterbore 133 a bent passageway 134 extends upwardly to a junction with the pipe 48 which in this case extends downwardly through the hole 47. The ball check valve 49 of Figure 3 is omitted in Figure 12, being replaced by the ball check valve 130. Furthermore, two pipes 48 are employed in the power generating unit 111 in place of the single pipe in the power generating unit 11.

In order to control the fuel passing upward through the pipes 48, a valve plunger or valve member 135 is reciprocably mounted in the valve bore 123 and is in the form of a rod or cylinder having an annular valve groove 136 at approximately its mid-portion. The groove 136 is so located relatively to the top end 137 of the valve plunger 135 that when the valve plunger 135 moves downward, the groove 136 first establishes communication between the ports 125 and the passageways 126 before the port 124 is uncovered by the top 137 of the valve plunger 135.

The valve plunger 135 is connected at its lower end to a so-called Sylphon bellows or sealed resilient bellows 138, the lower end of which is anchored to a U-shaped bracket 139 by a bolt 140 threaded through the bracket 139 and into the lower end of the bellows 138. The bracket 139 is secured to the underside of the partition 46.

In the power-generating unit 111, the spark plug 71 is shielded from possible short-circuiting by being enclosed in an elbow-shaped casing 141 (Figure 12) which is secured at its upper end to the extension 72 and at its lower end is seated in a tubular connection or socket 142.

The fuel supply and control system, generally designated 145, for the modified rotary lifting device 110 (Figure 16) is mounted in the fuselage including the member 17 (Figure 3) and includes an air compressor 146 driven by a motor 147 on a base 148 and having air intake and discharge lines 149 and 150 respectively, the latter containing a combination pressure-responsive switch and control valve 151, the normally-closed switch 152 of which is in circuit with the motor 147 and controls the energization thereof through the lines 153 and 154, the line 155 running directly to the motor 147. The discharge pipe 150 controlled by the valve 151 discharges into a compressed air

storage tank 156 from which a line 157 runs to the top of a fuel tank 158 above the level of the liquid therein. An electro-magnetic valve 159 operated by a solenoid 160 energized from the lines 161 and 162 controls the pressure in the main fuel tank 158. The latter has an air-tight filling spout 163 and also an air pressure pipe 164 connected to the actuating motor 165 of a normally-open pressure-responsive switch 166 which closes the circuit between the lines 167 and 168 in response to a predetermined rise in pressure in the top of the fuel tank 158. The fuel supply pipe 44 in both forms of the invention shown in Figures 3 and 12 extends downward into the tank 158. The lines 168 and an additional low tension line 169 supply low tension current to the primary of a spark coil 170 from the secondary terminals of which a line 171 runs to a ground connection 172 on the power generating unit 11 or 111. The high tension line 73 is connected to the other secondary terminal of the spark coil 170 and, as previously explained, extends upward through the tube 74 to the spark plug 71.

The modified rotor assembly 173 of the modified rotary lifting device 110 (Figure 13) differs slightly from the rotor assembly 12 (Figure 5) in several respects. The branch tube 87 with its spray orifices 88 is omitted and the secondary fuel tube 79 proceeds uninterruptedly into the arcuate jet discharge tube 15. The main fuel pipe 78, on the other hand, is bent as at 174 after passing through a hole 175 in the side wall of an annular air intake port 176 which extends farther into the tube 15 than its counterpart 92 in Figure 5. Mounted on the inner end of the tube 78 beyond the bend 174 is a fuel spray nozzle 177 which discharges fuel tangentially or circumferentially into the tube 15 and replaces the nozzle ring 96 with its spray orifices 91 of Figure 5. The remainder of the construction of Figure 13 is similar to that of Figure 5.

The jet discharge tube construction shown in Figures 14 and 15 also differs from that shown in Figure 9 in that the modified dynamic pressure head 197 is automatically controlled by a centrifugally responsive valve 198, whereas the dynamic pressure head 97 of Figure 9 is not so controlled. The secondary fuel pipe 79 is connected to a socket 199 in the supporting arms 200 of the dynamic pressure head 197 (Figure 15) and from the socket 199 a passageway 201 leads to a valve bore 202 from which an L-shaped passageway 203 leads through the supporting body 204 of the dynamic pressure head 197 into a chamber 205 formed within a hollow pointed tapered casing member 206 which is threaded as at 207 onto a boss 208 projecting axially along the tube 15 from the body 204. The body 204 is bulbous-shaped and with the casing portion 206 forms a tear drop-shaped assembly similar in shape to the dynamic pressure head 97 of Figure 9 and similarly supported by the arms 200 of streamlined or airfoil cross-section (Figure 15). From the chamber 205 approximately U-shaped passageways 209 (Figure 14) lead to outlets or jet orifices 210 corresponding to the orifices 99 of Figure 9.

Reciprocably mounted in the valve bore 202 is a valve plunger 211 (Figure 14) having an annular cutaway portion 212 adapted to be brought into communication with the ends of the passageways 201 and 203 where they join the valve bore 202. The valve plunger 211 is urged outward or to the right in Figures 14 and 15 by a compression spring 213 disposed between the boss 208 and

the head 214 on the external end of the valve plunger 211.

The opening and closing of the valve plunger 211 relatively to the passageways 201 and 203 is controlled by a flyball lever 215 which is pivoted as at 216 (Figures 14 and 15) upon arms or ears 217 which extend axially along the interior of the tube 15. The flyball lever 215 is provided at one end with a flyweight or flyball 218 and at its opposite end with an arm 219 drilled as at 220 to receive an eye-bolt 221. Secured to one end of the eye-bolt 221 is a tension spring 222, the opposite end of which is secured to a drilled ear or boss 223 projecting axially from the boss 208. The flyball lever 215 is provided with a cam portion 224 engageable with the head 214 of the valve plunger 211.

Operation of the modified rotary lifting device

The operation of the modified rotary lifting device 110 (Figures 12 to 16 inc.) in general follows the operation of the rotary lifting device 10 as previously described above except for changes in operation brought about by the changes in construction just described. The action of the fuel supply system 145 of Figure 16 is nearly the same for both forms of the invention, as this system 145 is preferably used for both forms of the invention.

In the operation of the modified rotary lifting device 110, the motor 147 (Figure 16) energized from a storage battery, drives the air compressor 146 and causes it to pump air through the pipe 150 and pressure-responsive valve and switch 151 into the air tank 156. When a predetermined pressure is reached in the tank 156, this pressure closes the valve 151 and also opens the normally closed switch 152, de-energizing the motor 147 and causing the compressor 146 to cease operation. Air pressure is thus locked in the tank 156 between the valves 151 and 159.

To start the rotary lifting device 10 or 110 (Figure 16), the valve 159 is opened by energizing the lines 161 and 162 to cause the solenoid 160 to operate the valve 159, whereupon compressed air is admitted through the pipe 157 to the space above the liquid level in the main fuel tank 158, forcing the liquid fuel upward in the tube 44 through the check valve 114 into the first stage tank 45 where it builds up pressure and gradually compresses the bellows 138. The latter, when so compressed, pulls the valve member 135 downward until the annular groove 136 is aligned with the ports or passageways 125 and 126, permitting the liquid fuel to pass from the chamber 45 upward through the pipes 48 into the upper or second stage tank 55. The upper tank 55 is filled in this manner until a back pressure is built up sufficient to further compress the bellows 138, pulling the top 137 of the valve member 135 below the upper side wall port 124 (Figure 12). This permits fuel to pass through the port 124, the upper end of the valve bore 123, the passageways 122 and 121, through the strainer 119, into the orifice 120 of the spray nozzle 116, causing a spray of fuel upwardly from the nozzle 116.

At the same time, the same buildup of back pressure also operates the actuating motor 165 of the normally open pressure-responsive switch 166 to close the switch 166 and energize the spark coil 170. A spark then jumps across the electrodes of the spark plug 11 by reason of the high tension current passing through the secondary leads 73 and 171 from the spark coil 170, igniting the fuel spray which has emerged from the nozzle 116 and has traveled upwardly in the vertical air

tube 63. The ignition of the fuel in this manner causes the burnt gases and other products of combustion to be expelled rapidly through the converging inner ducts 84 into the jet discharge tubes 15 (Figure 13) in the direction of the arrows, causing the rotor assembly 12 or 173 to rotate, in the manner previously described. At the same time, additional fuel is sprayed through the nozzles 177 (Figure 13) into the jet discharge tubes 15, increasing the speed of rotation in the manner previously described. Air entering the annular air intake port 176 mixes with the spray of fuel from each nozzle 177 to form a combustible mixture.

The action of the modified dynamic pressure heads 197 is somewhat different from that of the dynamic pressure heads 97 described in connection with Figure 9 in that the outlet of the dynamic pressure heads 197 is automatically and centrifugally controlled. When the burning gases from the ducts 84 and nozzles 177 have almost reached their maximum expansion and velocity, the consequent rotation of the rotor assembly 173 and its discharge tubes 15 creates centrifugal force which causes the flyweights 218 on the flyball levers 215 (Figure 14) to move toward the centerline of the tube 15, causing the cam portion 224 thereof to shift the valve plunger 211 inward or to the left in Figure 14, bringing the annularly grooved portion 212 thereof opposite the ends of the passageways 201 and 203 so as to place them in communication. The hot high pressure fuel entering through the pipe 79 to each dynamic pressure head 197 is thus caused to flow into the chamber 205 (Figures 14 and 15) and thence through the passageways 209 and outlets 210 into the interior of the jet discharge tubes 15 into the path of the burning gases. This provides an additional thrust and consequently increased rotational velocity to the rotor assembly 173. The rotational velocity and the control of the centrifugally responsive valve 198 in each dynamic pressure head is thus maintained by increasing or decreasing the pressure in the first and second stage tanks 45 and 55 (Figures 12 and 16) in the above-described manner so as to control the amount of liquid fuel ejected from the respective burner nozzles or jet openings.

What I claim is:

1. A jet-operated rotary lifting device comprising a support, a rotary structure rotatably mounted on said support and including a plurality of radially disposed lifting blades, a plurality of circumferentially disposed jet-discharge tubes connected respectively to said lifting blades, an internal combustion gas generator connected to said rotary structure, means for supplying fuel to said generator, and gas discharge conduits for conducting the burning gases from said generator to said jet discharge tubes, said gas generator having a combustion chamber with a fuel burner therein, an auxiliary fuel receptacle, said burner being connected to said receptacle, an igniter disposed adjacent said burner, a fuel container and a spirally disposed fuel scoop conduit having an inlet in said container and having an outlet connected to said jet discharge tubes.

2. A jet-operated rotary lifting device comprising a support, a rotary structure rotatably mounted on said support and including a plurality of radially disposed lifting blades, a plurality of circumferentially disposed jet-discharge tubes connected respectively to said lifting blades, an internal combustion gas generator connected

to said rotary structure, means for supplying fuel to said generator, gas discharge conduits for conducting the burning gases from said generator to said jet discharge tubes, said gas generator having a combustion chamber with a fuel burner therein, an auxiliary fuel receptacle, said burner being connected to said receptacle, an igniter disposed adjacent said burner, a fuel container and a spirally disposed fuel scoop conduit having an inlet in said container extending through said blades and having an outlet connected to said jet discharge tubes.

3. A jet-operated rotary lifting device comprising a support, a rotary structure rotatably mounted on said support and including a plurality of radially disposed lifting blades, a plurality of circumferentially disposed jet-discharge tubes connected respectively to the trailing edges of the tips of said lifting blades and extending arcuately along the circumferential path thereof, an internal combustion gas generator connected to said rotary structure, means for supplying fuel to said generator, and means for conducting the burning gases from said generator to said jet discharge tubes, said gas generator having a combustion chamber with a fuel burner therein, and an igniter disposed adjacent said burner, and said fuel supply means including an auxiliary fuel receptacle and said burner including a wick extending at one end into said fuel receptacle and at its other end into said combustion chamber.

4. A jet-operated rotary lifting device comprising a support, a rotary structure rotatably mounted on said support and including a plurality of radially disposed lifting blades, a plurality of circumferentially disposed jet-discharge tubes connected respectively to the trailing edges of the tips of said lifting blades and extending arcuately along the circumferential path thereof, an internal combustion gas generator connected to said rotary structure, means for supplying fuel to said generator, and means for conducting the burning gases from said generator to said jet discharge tubes, said gas generator having a combustion chamber with a fuel burner therein, an auxiliary fuel receptacle, said burner being connected to said receptacle, an air scoop having an intake disposed externally of said container and having an air passageway leading to said combustion chamber from the exterior thereof, and an igniter disposed adjacent said burner.

5. A jet-operated rotary lifting device comprising a support, a rotary structure rotatably mounted on said support and including a plurality of radially disposed lifting blades, a plurality of circumferentially disposed jet-discharge tubes connected respectively to the trailing edges of the tips of said lifting blades and extending arcuately along the circumferential path thereof, an internal combustion gas generator connected to said rotary structure, means for supplying fuel to said generator, and means for conducting the burning gases from said generator to said jet discharge tubes, said gas generator having a combustion chamber with a fuel burner therein, an air scoop leading to said combustion chamber from the exterior thereof, an auxiliary fuel receptacle, and said burner including a wick extending at one end into said fuel receptacle and at its other end into said combustion chamber.

6. A jet-operated rotary lifting device comprising a support, a rotary structure rotatably mounted on said support and including a plurality of radially disposed lifting blades, a plurality

of jet-discharge tubes disposed adjacent the ends of said blades and having outlets extending therefrom in a direction opposite to the direction of rotation of said blades, a casing connected to said structure, a fuel container in said casing, an auxiliary fuel receptacle, a combustion chamber in said casing adjacent said fuel container, a fuel burner in said combustion chamber connected to said receptacle, an igniter in said combustion chamber disposed adjacent said burner, means for supplying air to said combustion chamber, means for supplying fuel to said container, gas discharge conduits connecting said combustion chamber to said jet-discharge tubes for conducting the burning gases from said combustion chamber to said jet-discharge tubes, and a primary fuel duct leading from said fuel container to at least one of said jet discharge tubes.

7. A jet-operated rotary lifting device comprising a support, a rotary structure rotatably mounted on said support and including a plurality of radially disposed lifting blades, a plurality of jet-discharge tubes disposed adjacent the ends of said blades and having outlets extending therefrom in a direction opposite to the direction of rotation of said blades, a casing connected to said structure, a fuel container in said casing, an auxiliary fuel receptacle, a combustion chamber in said casing adjacent said fuel container, a fuel burner in said combustion chamber connected to said receptacle, an igniter in said combustion chamber disposed adjacent said burner, means for supplying air to said combustion chamber, means for supplying fuel to said container, gas discharge conduits connecting said combustion chamber to said jet-discharge tubes for conducting the burning gases from said combustion chamber to said jet-discharge tubes, a primary fuel duct leading from said fuel container to at least one of said jet-discharge tubes, a primary auxiliary fuel spray nozzle on said primary fuel duct within said jet-discharge tube and an auxiliary air supply conduit in said rotary structure having an air intake disposed in the direction of rotation of said rotary structure and an air outlet communicating with said combustion chamber.

8. A jet-operated rotary lifting device comprising a support, a rotary structure rotatably mounted on said support, a plurality of radially disposed lifting blades connected to said rotary structure, a plurality of jet-discharge tubes disposed adjacent the ends of said blades and having outlets extending arcuately along the circumferential path of the tips of said blades in a direction opposite to the direction of rotation of said blades, a casing connected to said structure, a fuel container in said casing, a combustion chamber in said casing adjacent said fuel container, an igniter in said combustion chamber, means for supplying air to said combustion chamber, means for supplying fuel to said container, and gas discharge conduits connecting said combustion chamber to said jet-discharge tubes for conducting the burning gases from said combustion chamber to said jet-discharge tubes, said air supplying means including an air scoop projecting exteriorly of said rotary structure and a spirally disposed vane leading from said air scoop to said combustion chamber.

9. A jet-operated rotary lifting device comprising a support, a rotary structure rotatably mounted on said support, a plurality of radially disposed lifting blades connected to said rotary structure, a plurality of circumferentially disposed jet-discharge tubes connected respectively

to the trailing edges of the tips of said lifting blades and extending arcuately along the circumferential path thereof, an internal combustion gas generator connected to said rotary structure, means for supplying fuel to said generator, and means for conducting the burning gases from said generator to said jet discharge tubes, said gas generator having a combustion chamber and a fuel container; said fuel supply means including an auxiliary fuel receptacle, a conduit connecting said fuel receptacle to said combustion chamber, a fuel-pressure-responsive valve in said conduit responsive to the pressure of fuel supplied to said receptacle to open and close said conduit, and a spray nozzle on said conduit arranged to spray fuel into said combustion chamber.

10. A jet-operated rotary lifting device comprising a support, a rotary structure rotatably mounted on said support, a plurality of radially disposed lifting blades connected to said rotary structure, a plurality of jet-discharge tubes disposed adjacent the ends of said blades and having outlets extending arcuately along the circumferential path of the tips of said blades in a direction opposite to the direction of rotation of said blades, a casing connected to said structure, a fuel container in said casing, a combustion chamber in said casing adjacent said fuel container, an igniter in said combustion chamber, means for supplying air to said combustion chamber, means for supplying fuel to said container, gas discharge conduits connecting said combustion chamber to said jet-discharge tubes for conducting the burning gases from said combustion chamber to said jet-discharge tubes, a secondary fuel duct leading from said fuel container to the discharge end of at least one of said jet-discharge tubes, a secondary auxiliary fuel spray nozzle on said secondary fuel duct adjacent said discharge end, and a normally-closed centrifugally-responsive valve in said secondary fuel duct responsive to the attainment of a predetermined centrifugal force during the rotation of said rotary structure for opening 40 communication through at least one of said sec-

ondary fuel ducts to at least one of said jet discharge tubes.

11. A jet-operated rotary lifting device comprising a support, a rotary structure rotatably mounted on said support and including a plurality of radially disposed lifting blades, a plurality of circumferentially disposed jet-discharge tubes connected respectively to the trailing edges of the tips of said lifting blades and extending arcuately along the circumferential path thereof, an internal combustion gas generator connected to said rotary structure, said gas generator having a combustion chamber with a fuel burner therein, means for supplying fuel to said burner, means for conducting the burning gases from said generator to said jet discharge tubes, and a fuel igniter disposed adjacent said burner, said fuel supplying means including, a main fuel tank, a fuel supply conduit system connecting said burner to said tank, a compressed gas source connected to said tank, and a pressure-responsive device in said conduit system responsive to the attainment of a predetermined pressure in said conduit system for initiating operation of 25 said igniter.
